[57] CLAIM

The ornamental design for a vehicle cabinet, as shown and described.

DESCRIPTION

FIG. 1 is a perspective view of the vehicle cabinet of the present invention looking from the upper left;

FIG. 2 is a perspective view of the vehicle cabinet exterior surface of FIG. 1 looking from the upper right in this figure; FIG. 3 is a bottom view of the vehicle cabinet exterior surface of FIG. 1; and,

FIG. 4 is a view like that shown in FIG. 2 showing a television set and video cassette recorder in broken lines. The rear of the vehicle cabinet is plain and unornamented and forms no part of the claimed design.

The broken line showing of the television set and video cassette recorder in FIG. 4 is for illustrative purposes only and forms no part of the claimed design.
